UNITED STATES PATENT OFFICE

2,568,388

ANNUAL RADIATING DRUM AIR HEATING
FURNACE

Harte H. Diggins, Woodstock, Ill.

Application July 17, 1948, Serial No. 39,231

1 Claim. (Cl. 126—102)

1

The present invention relates to the art of heating space by means of hot or warm air; and it has for its object to produce an efficient and inexpensive heater for this purpose that can be manufactured in a simple manner in indefinite numbers, both in small sizes for heating a single room or other small space and in large sizes to supply central heat for whole dwellings and other large spaces.

In carrying out my invention I use sheet metal for all of the main parts except, of course, the burner, and unite them by crimping meeting marginal portions of the sheets in any conventional manner. Therefore, viewed in one of its aspects, the present invention may be said to have for its object to create a heater of any desired capacity from material comparable to that used in ordinary stove pipes, for example, and having its joints made mainly or entirely by crimping the said sheet metal.

The various features of novelty whereby the present invention is characterized will herein-after be pointed out with particularity in the claim, but, for a full understanding of the invention and of its objects and advantages, reference may be had to the following detailed description taken in connection with the accompanying drawings, wherein:

Figure 1 is a front elevation of a heater of one of the larger sizes embodying the present invention; Fig. 2 is a rear view of the heater; Fig. 3 is a top plan view of the heater; Fig. 4 is a vertical section through the heater, on a somewhat larger scale than Figs. 1—3; Fig. 5 is a section on line 5—5 of Fig. 4; Fig. 6 is a section, on a still larger scale, showing the conventional "stove pipe" seam used in the various shells which may be one taken on line 6—6 of Fig. 4 or of Fig. 12, for example; Fig. 7 is a section through a second form of seam, used in connecting the flaring ends of the inner shell member of the annular drum; Fig. 8 is a view similar to Fig. 7, showing the seam between the flaring part in Fig. 7 and the outer of the two shells that form the drum; Fig. 9 is a transverse section through a corner of the heater casing; Fig. 10 is an elevational view of the cap for the fire tube before assembly on the latter, a portion being broken away; Fig. 11 is an elevational view of one of the halves of which the cap is made, before the halves are joined together; Fig. 12 is an elevation view of one of the exhaust tubes before being assembled in the heater; and Fig. 13 is an elevational view of one of the pass-overs for the hot combustion gases, ready for assembly in the heater.

2

In the particular heater shown in the drawings there are five coaxial cylindrical shells. The inner shell 1 forms the body of the fire tube; the next smaller, shell 2, is adapted to absorb radiant heat from the fire tube; the next two shells, 3 and 4, are connected together, as will be explained later, to form an annular drum into which the combustion gases pass before leaving the heater; and the outermost shell 5 absorbs heat radiated from the drum. Radiant shell 2 also absorbs some of the heat radiated from the drum. The radiant shell 2 is preferably the longest, extending well below the others, and the radial distance between the same and the fire tube is preferably about twice as great as the corresponding distance between the same and the drum. The top of shell 1 is closed by a cap 6 that decreases in cross sectional area from the base to the top; the shape illustrated being conical.

Each shell is made from a single sheet rolled into the form of a cylinder, with meeting edges joined by a conventional stove pipe seam 7, as shown in Fig. 6.

The inner shell member 3 of the drum is shorter than the outer one, 4, corresponding ends being connected together by flaring band-like ring sections 8, 8. The joints between shells 3 and 4 and these ring sections are illustrated in Figs. 7 and 8; Fig. 7 showing the joint between the lower ring section, on the right hand side of Fig. 4, and shell 3, while Fig. 8 shows the joint in that same region with the lower end of shell 4. It will be seen that the ring has an upturned flange 8^a at the end of smaller diameter and a downturned flange 8^b at the larger end. Shell 3 is crimped or bent, as at 3^a, to form with the ring and its upper flange a so called Pittsburgh lock, whereas the lower end of shell 4 is simply crimped, as at 4^b, to embrace the lower flange 8^b.

The fire tube, drum, and intermediate radiant shell are shown as being held together by three like tubular pass-overs 9; these being oval in cross section and being assembled in the structure with their long transverse axes vertical. The pass-overs are like pieces of stove pipe, each containing the conventional stove-pipe seam 7^a as shown in Fig. 13, and each being provided with external beads 10 and 11 a short distance from its ends. Shells 1, 2 and 3 contain registering holes through which the pass-overs extend; shells 1 and 3 abutting against beads 10 and 11, respectively, and the marginal portions 9^a and 9^b beyond the beads being flanged outwardly to clamp the adjacent shells against the beads. Shell 2 is

loose on the pass-overs, but is held in axial alignment by spacers 12, interposed between the same and shell 3. Shell 5 is connected to shell 4 by means of intermediate members 16.

Two of the pass-overs are near the top of the fire tube, diametrically opposite each other, while the third is near the bottom with its longitudinal axis at right angles to a vertical plane containing the corresponding axes of the upper pass-overs.

The combustion gasses flow from the fire tube into the drum through the pass-overs, and escape from the drum through two like exhaust tubes 14, 14 of which one is shown in detail in Fig. 12. Each exhaust tube has a longitudinal stove pipe seam 7^b, and an external bead 15 near one end, to leave a narrow marginal portion 14^a outwardly from the bead. Two openings, arranged close together, are provided in the shell member 4 of the drum, diametrically opposite the lower pass-over, but somewhat lower down, for the reception of the marginal portions 14^a of the exhaust tubes; these marginal portions being then flanged laterally on the inner side of shell 4 to fix the exhaust tubes to the shell. The exhaust tubes pass through holes in the outer shell 5 so that, when spacers 16 are placed between that shell and shell 4, as shown in Fig. 5, shell 5 is locked in its proper position relative to the other shells.

The fire tube fits at its lower end over a short sleeve section 17 constituting an outlet through the top of a combined draft tube and burner housing 18, close to one end of the latter; such housing being a rectangular box-like structure open at the end that projects farthest beyond the fire tube, namely the right hand end in Fig. 4. The lower end of the radiant shell 2 partially embraces the part of housing 18 that becomes hot, so as to absorb some of the radiant heat emitted from the latter.

The unit heretofore described is housed in a cabinet or casing 19 that is square, with rounded corners, in cross section, and is made from sheet metal without extraneous fastenings. The two exhaust tubes 14 extend through the rear wall of this casing into a draft diverter 20 which is simply a little housing open at the bottom and having in the top an outlet opening surrounded by a short sleeve-like part 21 to receive a flue pipe, not shown. This outlet, as best shown in Fig. 5, has its center on a radius bisecting the angle between the exhaust tubes and outwardly from the ends of these tubes; whereby any back draft will go straight down past these tubes and not through them into the heater. The casing has louvers 22 in the lower part of the rear wall and has in the lower part of the front side a door 24 containing louvers 25; the door giving access to the interior of the draft tube and burner housing when removed as in Fig. 4. The top wall of the casing is provided with projecting sleeve-like elements upon which may be slipped pipes for carrying heated air to spaces to be heated. There may be any desired number of these elements, five of them, 26, 27, 28, 29 and 30 being shown.

The front end of the combined draft tube and burner housing may be fastened to or be supported by the walls of the casing in any suitable manner. In the arrangement shown, there is a transverse angle bar 31 fastened to the top of this housing and, in turn, to the front wall of the heater casing above the door opening. There is also a support 32 below the housing, this support extending between and being carried by the side walls of the casing.

It will be seen that the draft tube and burner housing is divided into upper and lower compartments by a horizontal partition 34. The burner 35, shown only in outline in broken lines, extends through the partition so that air may be supplied to the burner through the lower compartment and to the flame through the upper compartment.

The heater casing has in the front wall, above the door 24, a panel 36 interlocked with the two vertical side members of the casing by means of joints 31, shown in detail in Fig. 9. There is a similar panel 38 in the rear side of the casing or cabinet, but extending throughout the entire height of the latter. Top and bottom walls 19^a and 19^b, respectively, having crimped connections with the vertical walls, complete the cabinet.

As heretofore explained, the cap 6 on the fire tube may be of any desired shape and construction. In the arrangement shown in Fig. 10 and Fig. 11, it is formed of two sheet metal half cones 6^a that meet in a plane containing the axis of the cone. At their meeting edges are flanges 39 that may be welded together or be crimped to produce a seam 40. A flange or short skirt 41 along the lower edge adapts the cap for attachment to the shell member of the fire tube.

It will thus be seen that I have produced a very simple heater composed of a complete heat interchange unit and a separate draft tube and burner housing that are readily assembled in a casing which, like the rest of the structure is made from sheet metal; so that it is an easy matter to build a heater of any desired capacity at a minimum cost in time, labor and material. Because there are three annular layers of air that are heated either by direct contact with or radiation from surfaces heated directly by the fire or hot combustion gases, and a fourth annular layer, just inside the heater casing, that flows past a surface that has received radiant heat from one of the aforesaid surfaces; there is a maximum transfer of heat from the source to the air to insure high efficiency; and the temperature of the heater casing is kept low. It will also be seen that, because of the two separate sources of supplying air for supporting combustion and the easy access to the burner and its controls, it is a simple matter to achieve a high degree of efficiency in the combustion of fuel.

It should further be noted that the flaring inlet for the annular air space immediately surrounded by the drum insures that more air will rise through this space than would otherwise be the case; and that the flaring outlet for this annular space and the conical cap on the fire tube permit ready expansion of the heated air leaving the inner annular spaces and approaching the distributing pipes.

A very important feature of my invention resides in the manner of making and assembling the parts of the heater. The five shells, the tubular pass-overs and the exhaust tubes are cut to pattern from flat sheet material, and the required openings are provided therein. The flat sheets are then rolled into their intended cylindrical or oval shapes, as the case may be, and preliminary deformation of marginal portions thereof, where required, is effected. Either before or after the longitudinal seam is made in the fire tube, the concave end of each completed pass-over is inserted in the hole prepared for it in the fire tube, until bead 10 engages the outer surface of the latter. Then the

flanges 9^a are bent up by a suitable crimping tool so as to clamp the wall of the fire tube between these flanges and the beads 10. The longitudinal seam for the fire tube is then completed if that had not previously been done, and cap 6 is applied.

Holes 2^a in radiant shell 2 are large enough to allow the beaded outer ends of pass-overs 9 to pass freely through the same. If the longitudinal seam in this shell has not yet been completed, assembly of this shell on the pass-overs may be through wrapping it, as is were, around the fire tube. Where shell 2 has already been completed, it need only be sprung into a shape that is a little oval in cross section, to give it a transverse axis a little greater than the distance between the outer ends of the two upper pass-overs; thereby permitting the shell to slip down past the latter. Then the lower end of this shell is sprung at its lower end to produce an oval shape whose long axis is at right angles to the oval shape still retained by the upper part of the shell. This permits the lower end of the shell to move down past the lower pass-over. The downward movement of the shell is continued and the angular position is adjusted until each hole therein registers with one of the pass-overs. When this occurs, the shell springs back into cylindrical shape, as the beaded outer ends of the pass-overs freely pass through said holes.

Shell 3 is applied in about the same manner as shell 2, although it need be sprung to a lesser extent because its normal diameter is equal to the distance between the beads on the outer ends of the two upper pass-overs. In other words, only the flange portions on the outer ends of the pass-overs need enter the holes in the shell, because the shell is intended to abut against the beads adjacent to these flanges. The flanges are then bent up to clamp the shell against the bands and fasten it rigidly to the fire tube.

The manner of applying flared ends 8 of the drum and shells 4 and 5 needs no explanation,

except that the exhaust tubes 14 must be attached to shell 4 before the latter becomes a part of the completed drum.

It should further be noted that, although I prefer to make all joints through crimping, many of the advantages of my invention are retained even through some or all of such joints are welded.

I claim:

In a heater, a series of concentric shells permanently connected together into a single rigid unit, the innermost of said shells constituting a fire tube, two intermediate shells forming an annular heating drum, the drum being spaced apart from both the fire tube and the outermost shell to provide a plurality of annular open-ended spaces for the passage of air to be heated, an exhaust tube extending outwardly from the lower part of the drum through said outermost shell, a plurality of pass-overs extending radially between and fixed to the fire tube and the drum to connect their interiors together and serve to support the drum, two of the pass-overs being near the top and another being toward the bottom and diametrically opposite the exhaust tube, and a separate combined draft tube and burner housing connected to and closing the lower end of the fire tube.
